FLEXIBLE GUN MOUNT CONTROL

Clem G. Trimbach, Eggertsville, and Camille R. Lemonier, Kenmore, N. Y., assignors, by mesne assignments, to Curtiss-Wright Corporation, a corporation of New York

Application April 14, 1936, Serial No. 74,278

6 Claims. (Cl. 89—37.5)

This invention relates to gun mounts, and particularly comprises improvements in flexible machine gun mounts for aircraft of the type disclosed in Trimbach Patent No. 1,968,182, and 5 Trimbach application Serial No. 7,478, filed February 21, 1935.

The invention contemplates improvements in the means by which a gun carriage, rollable along a track, may be readily locked to the 10 track, in substantially any position thereon, and also contemplates means by which the carriage may be unlocked from, and moved along the track by a single motion on the part of the gunner. Particularly gun carriages of the prior art have 15 necessitated manual operation of the carriage wherein a handle is provided which is movable in one sense to unlock the carriage and movable in another sense to move the carriage on the track. In this invention, we provide a member which 20 may be acted upon in either direction by the knee of the gunner, initial motion of the member serving to unlock the carriage from the track, and subsequent motion in the direction in which it is desired to move the carriage, effecting such movement of the carriage.

An object of the invention is to provide knee-operated means by which a gun carriage may be locked to or unlocked from, or moved along, a track.

30 A further object is to provide a corrugated element on the track adapted to be engaged by a locking element on the carriage, the conformation of the corrugated member being such that, regardless of the position at which the carriage 35 may stop on the track, the carriage locking member will engage upon one of the corrugations and move the carriage to such a position that the locking member will firmly lock the carriage to the track.

40 Further objects will be apparent from a reading of the subjoined specification and claims, and from a consideration of the accompanying drawings, in which:

Fig. 1 is a diagrammatic elevation of a track 45 and a gun carriage incorporating the provisions of this invention;

Fig. 2 is a front elevation of part of a gun track and a carriage mounted thereon;

Fig. 3 is an end elevation of the gun carriage 50 and the track in section;

Fig. 4 is a section on the line 4—4 of Fig. 2;

Figs. 5, 6 and 7 are sections, respectively, on the lines 5—5, 6—6 and 7—7 of Fig. 3;

Figs. 8 and 9 are sections, respectively, on the 55 lines 8—8 and 9—9 of Fig. 2; and

Fig. 10 is a perspective view of one of the carriage elements.

As a basic organization with which this invention is adapted to be used, we show a track 11 having grooves 12 formed on the upper, lower and inner faces thereof. A carriage 13 comprises a channel member embracing the upper, lower and inner faces of the track and carrying rollers 14 engaging the respective track grooves. At the upper part of the carriage 13 is mounted a gun adapter socket 15 releasably mounted in a yoke 16 by means of spring-pressed releasable bolts 17 and 18. The lower end of the yoke 16 is pivoted to the carriage 13 at 19, whereby, upon release of the bolts 18, the yoke may be swung 15 inwardly and downwardly about the pivots 19. By appropriate manipulation of the bolts 17 or 18, the socket 15 may be removed from the gun carriage, or may be swung inwardly or outwardly with respect thereto, to provide for stowing of 20 a mounted machine gun within the aircraft.

Upon the lower inner face of the track 11, a strip 20 is attached as by screws 21, the exposed face of this strip comprising a series of corrugations or undulations 22. Mounted upon the lower 25 part of the carriage 13, on substantially horizontal pivots 23, are coaxial spaced levers 24, the upper portion of each lever 24 being formed at 25 for engagement with one of the corrugations 22. The lower portion of each lever 24 is provided with an adjustable ball contact element 26 adapted for engagement by a rocker 27 pivoted for swinging on a bolt 28 fixed centrally of the carriage 13. Each end of the rocker 27 is provided with a roller 29 for anti-friction engagement with the respective lever element 26, and each end of the rocker is also provided with a roller 30 which is adapted to bear against a suitably formed flat face on the inside of the carriage 13. Thus far, it will be apparent that 35 when the rocker 27 is in a substantially horizontal position, the rollers 29 will bear against the elements 26 to cause the levers 24 to engage the corrugated strip 20, thereby positively locking the carriage from movement along the track. 40 If the rocker 27 is tilted either clockwise or counter-clockwise, the levers 24 may swing outwardly from engagement with the strip 20 to permit the carriage to move along the track.

The rocker 27 is provided with an upward extension 31. A cross bolt 32 extends across the front of the carriage 13, this bolt having a rectangular central portion 33 lying just in front of the extension 31, the ends thereof providing stops for bushings 34 and 35 slidable along the 50 55

end portions of the bolt. These bushings are continually pressed toward a central position by means of compression springs 36 and 37 acting respectively between the ends of the carriage 13 and the faces of the bushings 34 and 35. These springs, acting through the bushings, serve at all times to urge the extension 31, and hence the rocker 27, toward a central position wherein the carriage is locked to the track. The springs 36 and 37 operate independently, the former being compressed when the carriage is unlocked and moved to the right, and the latter being compressed when the carriage is moved to the left. The uncompressed spring presses its bushing 35 against the stop 33, by which it does not act on the extension 31. Thus, a center position is established for the extension, being urged thereto by the springs, but each spring, because of the stop 33, does not act beyond the center.

20 The rocker 27 is provided with a pivot 38, upon which is suspended an operating lever 39 which may freely move in a plane substantially normal to the gun track. However, when the operating lever 39 is moved in the plane of the gun track, this motion is first effective in rocking the rocker 27 about its pivot 38 to unlock the carriage from the track. After the initial unlocking has been effected, continued movement of the operating lever 39 in the plane of the track will cause translation of the carriage along the track.

It is to be noted that the motion of the operating lever 39 may be initiated either to the right or left, as shown in Fig. 2, so that an operator, when he desires to move the carriage to the left, simply pushes the operating lever to the left. Conversely, when he wishes to move the carriage to the right, he pushes the operating lever to the right. When such pushing is stopped, the lever, by virtue of the action of the springs 36 and 37, will be moved to a central position to again lock the carriage to the track. Should the carriage stop at such a point on the track that the locking elements 25 are not opposite depressions in the corrugations of the strip 20, the conformation of said corrugations will cause the carriage to translate a slight amount until said elements engage the depressions of the corrugations whereby the rocker 27 will assume a horizontal position and the carriage will be irreversibly locked, until the lever 39 is again moved in the plane of the track.

In Fig. 2 is shown a spring 40 around part of the pivot 38, serving to urge the operating lever 39 to an operating position such as is shown in Figs. 1, 3 and 4. If the spring only were depended upon to hold the lever in position, it would be subject to oscillation since no positive operative position is provided by the spring. To prevent such oscillation, a latch mechanism, detailed in Fig. 9, is arranged, this comprising a latch 41 pivoted to the carriage 13 and pressed by a spring 42 to engage a dog 43 screwed to the lever 39. The latch 41, though urged into engagement with the dog 43, is not a positive lock, 65 due to the placement of the dog 43 below the pivot of the latch 41. Thus, when the gun is stowed, or the adapter socket 15 released from the carriage and dropped down, a dog on the socket 15 strikes the lever 39, moving the latter 70 inwardly under the carriage track 11 to an out of the way position. When the carriage is adjusted for firing, the lever 39 moves to the latched, operative position due to the action of the spring 40.

While we have described our invention in de-

tail in its present preferred embodiment, it will be obvious to those skilled in the art, after understanding our invention, that various changes and modifications may be made therein without departing from the spirit or scope thereof. We 5 aim in the appended claims to cover all such modifications and changes.

What is claimed is:

1. In a gun carriage movable along a track, a pair of spaced levers pivoted intermediate their ends to the carriage, one end of each lever being arranged for movement into contact with the track, a rock arm pivoted to said carriage between said lever pivots, the rock arm ends being arranged for engagement with the other ends of 15 respective levers, said rock arm when in substantially horizontal position, engaging both lever ends for holding both levers positively in track engagement, an operating member for rocking said rock arm, and resilient means acting directly upon said operating member for holding said rock arm in position for lever-end engagement.

2. In a lock for a gun carriage movable along a track, a member on the track comprising a 25 plurality of raised and depressed portions blending into one another to provide a plurality of undulations, an element movable with and with respect to the carriage, engageable with said undulations, and releasable positive means for holding said element within one of the depressed portions of said member, said element, upon release of said positive means, being disengaged from said member upon carriage movement along the track by virtue of the slope of said 35 undulations.

3. In a gun mount, a track having a locking surface thereon, a carriage slidable along said track, a locking surface engager pivoted to the carriage, and operating means pivoted on said carriage and swingable about its pivot to contact said engager and to enforce contact of the engager with said locking surface, said operating means being movable out of contact with said engager to allow of engager release and carriage 45 movement along the track.

4. In a gun carriage movable along a track, a lever pivoted to the carriage having a portion movable into locking engagement with the track, a rock arm pivoted to the carriage on an axis substantially normal to the lever axis having a portion engageable with said lever, in one position of the rock arm, for positively holding the lever in track engagement, said rock arm, when swung to either side of said one position, freeing 55 the lever from track locking engagement.

5. In a gun carriage movable along a track, a lever pivoted to the carriage having a portion movable into locking engagement with the track, a rock arm pivoted to the carriage on an axis 60 substantially normal to the lever axis having a portion engageable with said lever, in one position of the rock arm, for positively holding the lever in track engagement, said rock arm, when swung to either side of said one position freeing 65 the lever from track locking engagement, and resilient means normally urging said rock arm toward said one position.

6. In a gun carriage movable along a track, a lever pivoted to the carriage having a portion 70 movable into locking engagement with the track, a rock arm pivoted to the carriage on an axis substantially normal to the lever axis having a portion engageable with said lever, in one position of the rock arm, for positively holding the 75

lever in track engagement, said rock arm, when swung to either side of said one position, freeing the lever from track locking engagement, said track including an undulating series of raised and depressed portions with which said lever portion is adapted to engage, and said rock arm

being so located as to be able to move into said one position and to hold the lever only when the lever portion contacts the track in one of the depressed portions thereof.
